Lica is producing odd objects, like a small, white, porous, fibrous substance, a surface like bone, with a pale, reddish variegated, efflorescent, like bone, bone, or like a piece of seashells, or like some bone, granite.

medium, and a corresponding differential peak of carbon dioxide in the gas was observed. It is difficult to imagine a mechanism by which visible excited cylinders can form carbon dioxide molecules. However, it is possible that a secondary mechanism can involve excitation of the oxygen molecules by ultraviolet light.

UNITED STATES PATENT OFFICE

2,355,011

INTERNAL-COMBUSTION ENGINE

James Boyd Putnam, El Campo, Tex.

Application July 5, 1943, Serial No. 493,591

2 Claims. (Cl. 74—50)

This invention relates to new and useful improvements in internal combustion engines and more particularly to the rectilinear opposed piston type.

The principal object of the present invention is to provide an internal combustion engine of the opposed piston type wherein connecting rods are eliminated and substituted for by a cam and roller arrangement.

Other objects and advantages of the invention reside in certain points of adjustability and means for limiting wear on the several parts.

Other objects and advantages of the invention will become apparent to the reader of the following description.

In the drawings:

Figure 1 is a top plan view of the engine.

Figure 2 is a transverse sectional view taken on the line 2--2 of Figure 1.

Figure 3 is a fragmentary detailed sectional view showing adjustment means between the pistons and yokes.

Figure 4 is a top plan view of the pistons and yokes.

Figure 5 is a sectional view taken substantially on the line 5—5 of Figure 4.

Figure 6 is an end elevational view of the cam shaft.

Referring to the drawings wherein like numerals refer to like parts, it can be seen that numeral 5 denotes a cam housing from which project cylinder blocks 6, 6 on each of which is a cylinder head 7, equipped with the necessary spark plugs 8.

Numeral 9 denotes valves for the engine for controlling the fuel intake and scavenging operations but these form no part of the present invention.

The cylinders in the blocks 6 are arranged in opposed pairs and for each opposed pair there is an operating unit which is clearly shown in Figure 4 and which consists of a pair of pistons 10, 10 connected by a spider 11, this spider 11 consists of a pair of yokes 12, 12 connected at their upper and lower ends by bridge pieces a. The intermediate portions of the side members of the yokes 12 have enlargements 13 apertured to receive bolts 14. As shown in Figure 3, each piston 10 has a laterally disposed boss 15 apertured to receive the corresponding bolt 14 and each bolt 14 is equipped with a nut 16. Shims 17 may be placed between the boss 15 and the enlargement 13 of the corresponding yoke in order to compensate for wear between certain parts which will now be disclosed.

Numeral 18 denotes a shaft having a plurality of circumferentially grooved cams 19 thereon. The pistons 10 are equipped with bearing units 20, each having an outside race ring 21 which is rideable in the groove of the corresponding cam 19. The cams are arranged on the shaft in the firing order clearly shown in Figure 1 and further exemplified in Figure 6. The pistons will be prevented from any tendency to rotate by the fact that the rings 21 ride in the grooves of the cams 19. Any wear between the rings 21 and the cams 19 can be easily taken up by the addition of shims 17.

15 While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

as now is:
25 1. In an internal combustion engine, a housing having a pair of opposed cylinders projecting from opposite sides thereof, pistons reciprocable in said cylinders and having bosses projecting from opposite sides of the inner ends thereof, a spider rigidly connecting the adjacent ends of said pistons and embodying rigidly connected yokes having spaced side members extending transversely of the pistons at opposite sides of the latter and directly inwardly of said bosses, said side members merging at their upper and lower ends, and bridge pieces connecting adjacent merged ends of the yokes, said side members having intermediate enlargements, bolts passing through said bosses and said enlargements to rigidly connect the pistons to the spider, a shaft extending through the housing centrally between the cylinders, a circular cam eccentrically secured on said shaft, and rotatable within the spider, and roller elements mounted in the inner ends of the pistons and engaging the periphery of said cam.

40

2. In an internal combustion engine, a housing having a pair of opposed cylinders projecting from opposite sides thereof, pistons reciprocable in said cylinders and having bosses projecting from opposite sides of the inner ends thereof, a spider rigidly connecting the adjacent ends of said pistons and embodying rigidly connected yokes having spaced side members extending transversely of the pistons at opposite sides of the latter and directly inwardly of said bosses, said side members merging at their upper and lower ends, and bridge pieces connecting adjacent merged ends of the yokes, said side members hav-

ing intermediate enlargements, bolts passing through said bosses and said enlargements to rigidly connect the pistons to the spider, a shaft extending through the housing centrally between the cylinders, a circular cam eccentrically secured on said shaft, and rotatable within the spider, and roller elements mounted in the inner ends

of the pistons and engaging the periphery of said cam, said cam having a circumferential groove, and said roller elements embodying bearing units having outer race rings engaging in said groove of the cam.

JAMES B. PUTNAM.
